CLAIM

The ornamental design for an orthopaedic implant, as shown and described.

DESCRIPTION

FIG. 1 is a perspective view of an orthopaedic implant showing my new design;

FIG. 2 is a left side elevation thereof, the side opposite being a mirror image;

FIG. 3 is a top end elevation thereof, the end opposite being a mirror image; and,

FIG. 4 is a top plan view thereof, the side opposite being a mirror image.
